UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

SHOE FORM

Application filed August 24, 1929. Serial No. 388,106.

This invention relates to an improvement in a toe form adapted to be inserted into the toe of a shoe and adjusted to the proper amount so that the material of that part of the shoe upper is plumped out in order to give it the appearance which it would take when upon the foot of the wearer.

The object of this invention is to provide a shoe form comprising a hollow body of resilient material and a cross brace for connecting the walls of such body and by means of which the space between the walls of the body may be adjusted to expand or contract the form, one end of such cross brace being pivotally secured to one wall of the body and the other end engaging in any one of a transversely extending series of apertures in the other side wall.

Other objects will appear from a consideration of the following specification and of the drawings forming a part thereof and in which:

Fig. 1 is a plan view, with parts broken away, illustrating one embodiment of this invention;

Fig. 2 is a sectional view taken along the line 2—2 of Fig. 1;

Figs. 3, 4 and 5 are plan views similar to Fig. 1 of other embodiments of this invention; and

Fig. 6 is a sectional view taken along the line 6—6 of Fig. 4.

The toe form embodying this invention comprises a body 10 of celluloid or other resilient material having side walls 11 and 12 which terminate in ball flanges 13 and 14 respectively and means engaging the side walls for expanding or contracting the form. The various embodiments of the invention differ with respect to the means for expanding or contracting the form and hence the same reference characters will be applied to the body of the form throughout the specification and drawings.

The walls 11 and 12 of the body 10 in the embodiment shown in Fig. 1 are connected by a cross brace 15. One end of the brace is pivotally secured by a rivet 16 to the flange 13 and the other end is bent back upon itself to form a loop 17, terminating in a forwardly

extending portion 18 and an angularly projecting tongue 19. The loop 17 extends over the upper surface of the flange 14 while the section 18 extends below the lower surface (see Fig. 2). In the flange 14 are provided suitable laterally spaced means with which the end of the brace engages. Such means may be a row of laterally spaced apertures 20 which extend transversely of the flange and with any one of which the tongue 19 of the brace 15 may engage. It will be noted that the curved end of the loop 17 bears against the curved joinder of the wall 12 to the flange 14 and that the tongue 19 extends into the loop 17 of the brace. Moreover, when the form is inserted in a shoe the portion 18 will extend between the flange 14 and the sole of the shoe so that the tongue 19 will remain securely in the particular aperture into which it is placed before the form is inserted into the shoe.

The embodiment shown in Fig. 3 differs from that just described in that the cross brace 25 terminates at each end in a loop 26, a forwardly extending portion 27 and an angularly projecting tongue 28. Both the flanges 13 and 14 are provided with a row of laterally extending apertures 29. The loops 26 extend over the upper surfaces of the flanges 13 and 14, while the portions 27 extend below the under surfaces. This permits a further adjustment of the width of the form since both ends of the brace are adjustably and pivotally secured to the walls of the flange.

In the embodiment shown in Fig. 4 the cross brace 30 is similar in construction to the cross brace 15 of the first embodiment but is assembled below instead of above the flanges 13 and 14. One end of the brace 30 is pivotally secured to the flange 13 by a rivet 31 and the other end comprises a loop 32, a portion 33 and a tongue 34. In the flange 14 are provided a row of laterally extending apertures 35 which are adapted to receive the tongue 34 of the brace 30. The loop 32 extends below the flange 14 and the portion 33 extends above the flange. The tip 35 of the tongue 34 may be pointed as shown in Fig. 6 and projects through an aperture into the

100

loop 32 so that when the form is inserted in a shoe the tip will act as a spur or sprag engaging the upper surface of the shoe sole and thus prevent the inadvertent removing of the toe form.

The embodiment shown in Fig. 5 differs from that shown in Fig. 4 in substantially the same manner that the embodiment shown in Fig. 3 differs from that shown in Fig. 1. Thus the cross brace 40 terminates at each end in loops 41, forwardly extending portions 42 and angularly projecting tongues 43. Each of the flanges 13 and 14 are provided with a row of laterally extending apertures 44 which are adapted to receive the tongues 43 of the brace. The loops 41 and portions 42 extend below and above the flange 14. The tongues 43 may be pointed as in the Fig. 4 embodiment and in such cases projects through apertures into the loops and engage the inner sole of the shoe, thus forming a further insurance against slipping of the form out of position in the shoe after it has been properly inserted.

While several embodiments of the invention have been shown and described, I am not limited thereto since it will be understood that other embodiments can be made without departing from the spirit and scope of the invention as set forth in the following claims.

I claim:

1. A shoe form comprising a hollow body of resilient material and a cross brace connecting the walls thereof, one of said walls having a plurality of laterally spaced means extending transversely thereof with which one end of the brace engages whereby the walls are spaced a predetermined distance apart.

2. A shoe form comprising a hollow body of resilient material and a cross brace connecting the walls thereof, one of said walls having a row of laterally spaced apertures extending transversely thereof with which one end of the brace engages whereby the walls are spaced a predetermined distance apart.

3. A shoe form comprising a hollow body of resilient material and a cross brace connecting the walls thereof, said brace terminating at one end in a tongue, and the wall at said end having a plurality of laterally spaced means extending transversely thereof with which the tongue engages whereby the walls are spaced a predetermined distance apart.

4. A shoe form comprising a hollow body of resilient material and a cross brace connecting the walls thereof, said brace terminating at one end in a loop and a tongue which projects into the loop and the wall at said end having a plurality of laterally spaced apertures through which the tongue may project into the loop whereby the walls are spaced a predetermined distance apart.

5. A shoe form comprising a hollow body of resilient material having side walls provided with inwardly projecting flanges and a cross brace connecting the flanges, one of said flanges having a plurality of laterally spaced means extending transversely thereof with which one end of the brace engages whereby the walls are spaced a predetermined distance apart.

6. A shoe form comprising a hollow body of resilient material having side walls provided with inwardly projecting flanges and a cross brace connecting the flanges, one of said flanges having a row of laterally spaced apertures extending transversely thereof with which one end of the brace engages whereby the walls are spaced a predetermined distance apart.

7. A shoe form comprising a hollow body of resilient material having side walls provided with inwardly projecting flanges and a cross brace connecting the flanges, said brace terminating at one end in an angularly projecting tongue and the flange at that end having a plurality of laterally spaced means with which the tongue engages whereby the walls are spaced a predetermined distance apart.

8. A shoe form comprising a hollow body of resilient material having side walls provided with inwardly projecting flanges and a cross brace connecting the flanges, said brace terminating at one end in an angularly projecting tongue and the flange at that end having a row of laterally spaced apertures with which the tongue engages whereby the walls are spaced a predetermined distance apart.

9. A shoe form comprising a hollow body of resilient material having side walls provided with inwardly projecting flanges and a cross brace connecting the flanges, said brace terminating at one end in a loop and an angularly projecting tongue and the flange at that end having a row of laterally spaced apertures, the loop extending by one face of the flange and the tongue projecting through one of the apertures whereby the walls are spaced a predetermined distance apart.

10. A shoe form comprising a hollow body of resilient material having side walls provided with inwardly projecting flanges and a cross brace connecting the flanges, said brace terminating at one end in a loop, a forwardly extending portion and an angularly projecting tongue, the flange at that end having a row of laterally spaced apertures, the loop and forwardly extending portion above and below the surface of the flange and the tongue projecting through one of the apertures whereby the walls are spaced a predetermined distance apart.

11. A shoe form comprising a hollow body of resilient material having side walls provided with inwardly projecting flanges and

a cross brace connecting the flanges, said brace terminating at one end in a loop, a forwardly extending portion and an angularly projecting tongue, the flange at that end having a row of laterally spaced apertures, the loop and forwardly extending portion above and below the surface of the flange and the tongue projecting through one of the apertures into the loop whereby the walls are spaced a predetermined distance apart.

Signed by me at Auburn, N. Y., this 21st day of August, 1929.
